UNITED STATES PATENT OFFICE

127,881

DESIGN FOR AN ELEVATED TANK

James O. Jackson, Crafton, and Rodney W. De Vore, West View, Pa., assignors to Pittsburgh Des Moines Company, Pittsburgh, Pa., a corporation of Pennsylvania

Application March 4, 1941, Serial No. 99,348

Term of patent 14 years

To all whom it may concern:

Be it known that we, James O. Jackson and Rodney W. De Vore, citizens of the United States, and residents respectively, of Crafton, in the county of Allegheny and State of Pennsylvania, and of West View, in the county of Allegheny and State of Pennsylvania, have invented a new, original, and ornamental Design for Elevated Tanks, of which the following is a specification, reference being had to the accompanying drawing, forming part thereof.

The single figure is a perspective view of an elevated tank, showing our new design, the tank being symmetrical and having the same appearance when viewed from corresponding points.

We claim:

The ornamental design for an elevated tank, substantially as shown and described.

JAMES O. JACKSON.
RODNEY W. DE VORE.
